Patented Dec. 25, 1917.

UNITED STATES PATENT OFFICE.

ELLWOOD F. BENNETT, OF SAYRE, PENNSYLVANIA.

RAIL-BENDER.

1,251,172.

Specification of Letters Patent. Patented Dec. 25, 1917.

Application filed April 12, 1917. Serial No. 161,567.

To all whom it may concern:

Be it known that I, ELLWOOD F. BENNETT, a citizen of the United States, residing at Sayre, Pennsylvania, have invented certain new and useful Improvements in Rail-Benders, of which the following is a specification.

This invention relates to rail bending machines especially designed for "surface bending", that is, bending or straightening rails in their normal vertical plane.

The principal objects are to make a machine which may be moved to different positions along the rail and adjusted for the bending action very quickly and easily, and one which has powerful bending mechanism arranged so that the machine is relieved of any strains caused by the changing position of the bending plunger in the different positions that the rail assumes during one bending operation.

The characteristics and advantages of the invention will be further described so far as is necessary in connection with a detailed description of the accompanying drawing which shows one exemplifying embodiment of the invention. After considering this it will be evident to persons skilled in the art that the principles of the invention may be embodied in many different forms, and I do not limit myself to details except as claimed hereafter.

Figure 1 is a side elevation of one form of the invention shown in position on a rail to be bent.

Fig. 2 is a transverse section on the line *a—a*, Fig. 1.

Fig. 3 is a transverse section on the line *b—b*, Fig. 1.

Fig. 4 is a transverse section at *c—c*, Fig. 1.

Fig. 5 is a top plan, one of the yokes, however, being shown in transverse section.

Fig. 6 is a top plan detail of a part of the frame showing the yoke channels.

Fig. 1 shows the frame 1 of the machine placed upon a rail 2 to be bent. The rail is conveniently supported on transverse beams 3 to hold the base of the rail some distance from the ground, for reasons which will appear. Part 4 of the frame is preferably curved as shown to enable the frame to readily adapt itself to the tread of the rail when the machine is being adjusted for bending and during the bending operation. Adjacent to the point 4 the frame at each

side is provided with a vertical channel 5, these channels being defined by vertical ribs 6. Holding-down links or yoke members 7 (Figs. 1 and 5) are provided, each of which has a part 8 adapted to rest in one of the channels 5. At the upper end of each of the yoke members is a head 9 provided with lugs 10 having arc-shaped bottoms which extend over and rest upon the tops of ribs 6. Toward their lower ends the yoke members are curved outward and then inward forming hooks 11 arranged to lie beneath the rail base. The confronting faces of these hooks are preferably arranged to engage each other with a certain degree of looseness. Specific means for this purpose consist in a groove 12 formed in one of the hooks and a rib 13 formed on the other, this rib and groove fitting together somewhat loosely, as shown. A connecting plate 14 is provided which has a flat top to lie under the rail base, and on its bottom has beveled ribs 15 fitting with a certain degree of looseness the complementary channels 16 formed in the upper sides of hooks 11. In some cases, for the proper adjustment of the machine, one or more additional flat plates may be placed between the connecting plate 14 and the rail base. The yoke members are preferably provided with handles 17 which may consist of simple T-pieces screwed into the tops of the yoke members for easily handling them.

At one end of the frame 1 a wedge 18 is provided. This preferably has side flanges 19 to guide it in respect to the frame and other shallower flanges 20 to guide it in respect to the rail head. To adjust the wedge, a bell-crank lever 21 is provided. This has a loop form and is pivoted at each side to the frame at 22, conveniently by means of a bolt which may pass entirely through the frame. At each side the lever 21 has arms 23, slotted to engage studs 24 provided at the sides of the wedge.

At the same end of the frame a handle 25 may also be provided, consisting in this case of a U-shaped piece connected at each end to the bolt 22.

At the other end of the frame a head 26 is formed, vertically apertured to receive cylinder 27 of the hydraulic mechanism. Considerable clearance is provided in a longitudinal direction between the cylinder and the walls of the frame. Near the bottom the cylinder is provided with laterally extend-

ing lugs 28 and the head 26 is provided near the top with inwardly extending lugs 29. The tops of the cylinder lugs 28 are provided with curved faces 30 and between these faces and the bottoms of lugs 29 are inserted blocks 31 which have curved lower faces to coöperate with the curved surfaces 30 of the cylinder lugs. The described arrangement permits the hydraulic cylinder 10 with its plunger, during the bending operation, to oscillate with respect to the frame in a longitudinal direction, and so prevents the strains due the varying curvature of the rail and the varying position of the hydraulic plunger and cylinder from being communicated to the frame or from injuring any part of the bending mechanism.

The cylinder 27 carries suitable hydraulic mechanism for operating the plunger 32, 20 the lower end of which is grooved at 33 to conform approximately to the shape of the rail tread. Instead of hydraulic mechanism screw mechanism could evidently be located in the member 27.

25 When the wedge 18 is loosened the entire machine may be easily shifted along the rail to the desired point and when the plunger 32 is sufficiently retracted the machine is prepared for bending by tightening the wedge by means of handle 21. The hydraulic or other plunger operating means is then actuated to straighten the rail to the desired extent; the wedge is again loosened, the machine shifted, and so on. Whenever the 35 wedge is loosened, yoke members 7 may be quickly and easily removed to pass one of the beams 3 which support the rail or to permit the entire machine to be shifted to another rail, and these yoke members may 40 be as easily replaced owing to their separate construction and interlocking devices above described. At the same time the loose fit of the interlocking devices, comprising the plate 14, ribs 15 and grooves 16, lug 13 and groove 12, permit the hooked ends of the yoke members to move sufficiently in relation to each other and in relation to plate 14 to accommodate the parts to irregularities in the rail base.

45 While the machine is described for convenience as a bending machine, one of its chief purposes, as is evident from the foregoing, is to straighten bent rails; for in-

stance, in restoring old rails to serviceable condition, and for this purpose the machine 55 is especially well adapted.

I claim:—

1. In a rail bending machine, the combination of a frame, bending mechanism carried thereby, holding-down means to hold 60 the frame to a rail at a point between its ends, a wedge at one end of the frame engaging between the frame and the rail-head and adapted to quickly take up play when the machine is being adjusted for 65 bending, and means for connecting the wedge movably with the frame and for moving the wedge longitudinally in respect to the frame and rail.

2. In a rail bending machine, the combination of a frame having a curved bottom part to engage a rail head, vertical channels adjacent to the curved part, two separable yoke members located in the channels and having heads to engage the frame, said yoke 75 members having hook-shaped bottom ends to underlie the rail base and relatively loose interlocking means, a connecting plate arranged to lie between the hooks and the rail base and having relatively loose means for 80 interlocking with the hooks, a wedge and wedge operating means at one end of the frame and bending mechanism at the other end of the frame.

3. In a rail bending machine, the combination of a frame having a curved bottom part to engage a rail head, two separable yoke members having heads to engage the frame and having hook-shaped bottom ends to underlie the rail-base adjacent to said 90 curved part of the frame, a connecting plate arranged to lie between the hooks and the rail base and having means for interlocking loosely with the hooks, a wedge and wedge operating means at one end of the frame 95 and bending mechanism at the other end of the frame; said wedge having a flat bottom forming a flat surface engaging the rail head and extending along the head a substantial distance from one end of said 100 curved portion of the frame, and said connecting plate extending along the rail base for a substantial distance opposite to said curved frame portion.

ELLWOOD F. BENNETT.
